UNITED STATES PATENT OFFICE.

GEORGE A. MACBETH, OF ALLEGHENY, PENNSYLVANIA.

DESIGN FOR A LAMP-CHIMNEY.

SPECIFICATION forming part of Design No. 14,445, dated November 27, 1883.

Application filed October 10, 1883. Term of patent 14 years.

To all whom it may concern:

Be it known that I, GEORGE A. MACBETH, of Allegheny city, in the county of Allegheny and State of Pennsylvania, have invented a new and original Design for Lamp-Chimneys; and I do hereby declare the following to be a full, clear, and exact description thereof.

My design relates to the top of lamp-chimneys, its object being to impart to these lamp-chimneys a neat and attractive finish, and yet preserve thereto substantially the appearance of a circular edge or top.

It consists in a lamp-chimney having a flared mouth, and top or edge beyond said mouth ornamented with pinking, as shown, to impart a neat finish thereto.

The drawing illustrates by a side view my design. The chimney *a* is provided with the bulged portion *b*, the flared mouth *c*, and the edge *d*. This edge is ornamented with pink-

ing, as at *e*, the pinking ornamentation extending across the edge at about a right angle to the upper portion of the flared mouth, close to the top or edge *d*. This ornamentation imparts an exceedingly neat finish to the chimney-top without requiring the breaking of the outline of the edge, as is necessary in forming the ordinary crimped-top chimney.

What I claim, and desire to secure by Letters Patent, is—

The design for lamp-chimneys herein described, consisting in the flared mouth *c* and the top or edge *d*, ornamented with pinking, as shown, beyond said mouth.

In testimony whereof I, the said GEORGE A. MACBETH, have hereunto set my hand.

GEORGE A. MACBETH.
